UNITED STATES PATENT OFFICE.

FREDERICK GEORGE SCHRANZ AND WILLIAM H. HARMAN, OF PHILADELPHIA, PENNSYLVANIA, ASSIGNORS TO SOUTHWARK FOUNDRY & MACHINE COMPANY, OF PHILADELPHIA, PENNSYLVANIA, A CORPORATION OF PENNSYLVANIA.

CLOTHES WRINGER.

Application filed February 19, 1921. Serial No. 446,225.

To all whom it may concern:

Be it known that we, FREDERICK GEORGE SCHRANZ and WILLIAM H. HARMAN, citizens of the United States, and residents of Philadelphia, Pennsylvania, have invented certain new and useful Improvements in Clothes Wringers, of which the following is a specification.

Our invention relates to clothes-wringers, 10 more particularly those having frames made of metal, and one object of our invention is to provide a clothes-wringer with quick-acting release mechanism for the pressure-applying means for the squeeze-rolls.

15 A further object of our invention is to provide a clothes-wringer having a frame made wholly of metal with quick-acting release mechanism for the pressure-applying means for the squeeze-rolls, disposed adjacent one end of the upper squeeze roll; the 20 opposite end of said roll being automatically released in a manner hereinafter described.

A further object of our invention is to provide such quick-acting release mechanism 25 adjacent the gearing for the squeeze-rolls, and a still further object of our invention is to provide simple and efficient device for actuating the quick-release means and for this purpose we preferably employ a knock-off 30 device connected to one of the tension bolts forming part of the mechanism which retains the squeeze-rolls in place and applies the desired pressure thereto.

These and other features of our invention 35 are more fully described hereinafter, reference being had to the accompanying drawings, in which:

Figure 1, is a front elevation of one form 40 of clothes-wringer to which our improved quick-release device may be applied.

Fig. 2, is an end elevation looking in the direction of the arrow, Fig. 1.

Fig. 3, is a diagrammatic view illustrating 45 the position of the squeeze rolls after the operation of the quick-release device for the pressure-applying means therefor, and Fig. 4 is a fragmentary view illustrating certain details of construction, in section on the line IV-IV, Fig. 1.

50 The wringer frame to which the features constituting our present invention have been applied may be of metal, substantially U-shape in contour, and may comprise upright end portions with a lower connecting cross-

bar therefor; such frame being formed in one or a plurality of sections. In the drawings we have illustrated a wringer frame made of a plurality of sections, 1 and 2, fitting together on a median or substantially median line, as clearly illustrated in Fig. 2; 60 and secured together by suitable means, such for instance as rivets 3. While the use of our invention is not limited thereto, it is shown in connection with a wringer frame of the type illustrated and described in the 65 pending application of F. G. Schranz, filed February 19, 1921, Serial No. 446,226.

The sections 1 and 2 of the frame are provided with upright end portions 1^a and 1^b, and 70 2^a and 2^b, and these end portions may be provided with inwardly disposed flanges or ribs 4, providing channels adapted to receive bearing blocks 5, for the spindles 6, of squeeze rolls 7 and said bearing blocks 75 may have side ribs fitting the channels provided by the inner flanges of said end portions. These bearings are preferably of hard wood, and may be cut from a previously formed blank in the manner described in the application of F. G. Schranz, 80 filed Sept. 24, 1920, Serial Number 412,449. The bearing blocks 5 are applied to the upper side of the spindle of the upper roll and to the lower side of the spindle of the lower roll, and the lower bearing blocks may be 85 supported by inwardly disposed lateral projections carried by the upright end portions of the frame.

At one side of the wringer frame a housing 9 is provided, which may be integral 90 with the upright end portion of the frame, and this housing receives the gears 10 and 11 carried by the spindles 6 of the squeeze rolls 7. When the frame is made in a plurality of sections, such housing may be formed one half on each upright end portion 1^b and 2^b of the sections making up the frame.

Hinged at 12 to the upright end portions 1^a and 1^b, of the section 1, are cap members 13 and 14, which overlie the top of these end portions, as clearly illustrated in the drawings, and these cap members carry at their opposite ends bolts 15 and 16, hung from pivot pins 15^a and 16^a, mounted in pairs of ears 13^a and 14^a of the respective cap members; said bolts being adapted to underlie pairs of lugs 17 and 18, carried by the

upright end portions 2^a and 2^b of the section 2. The bolts 15 and 16 carry springs 19 interposed between washers 20 and 20^a also carried by the bolts and which may be 5 cupped to receive the ends of the springs; the washers 20 directly underlying the respective pairs of lugs 17 and 18. The bolts 15 and 16 may be provided with suitable nuts 21 engaging the end washers whereby the 10 tension of the springs 19 may be adjusted to an extent necessary to hold the parts securely in position and apply the desired pressure to the squeeze-rolls. The cap member 14 is provided with an extension 14^b, 15 preferably integral therewith, to overlie the gear housing 9.

In the present instance, the pressure-applying means for the squeeze-rolls 7, includes lugs or projections 22 disposed on the 20 under sides of the cap members 13 and 14, and preferably integral therewith; such lugs or projections directly engaging wear pieces 24, in the form of metal yokes, carried by the bearing blocks 5, for the spindle of the 25 upper squeeze-roll.

In this arrangement of quick-release mechanism for the squeeze-rolls, which mechanism is located at one side only of the wringer frame, the bolt 16 is provided with 30 an upwardly extending member 25, terminating in a hand plate 26, which extends over the squeeze rolls. The member 25 may be integral with the bolt 16 or rigidly secured thereto. Depression of the hand plate 26 or movement in the direction of the arrow α , 35 will swing the bolt 16 on its pivot pin 16^a, and release its spring 19 from engagement with the pairs of lugs 18 of the upright end portion; thereby relieving the pressure applied by said spring at one end of the squeeze-rolls. To completely release this 40 pressure-applying device it is only necessary to depress the handle 25 to the position shown by dotted lines in Fig. 2, whereupon the spring bolt 16 and the cap member 14 will be withdrawn from their operative engagement with the lugs 18, and the upper roll will be completely freed from the 45 pressure applied by the springs 19.

In this arrangement of quick-release device, only one end of the upper squeeze roll is relieved. As the opposite end of said upper roll is unsupported, however, the bearing block therefor being disposed above the 50 spindle to take the upward thrust, said upper roll is free to drop at its unsupported end and may rise at the end normally underlying cap member 14, when the latter has been removed as above described and, as 55 clearly indicated in the diagrammatic view, Fig. 3, completely removing all danger of injury to the operator should a finger or other portion of the hand be caught between the rolls; or to the wringer frame, should 60 the material passed between the rolls tend

to pile up. Should the upper squeeze roll continue to turn after the pressure at one end of the same has been released in the manner indicated, it will draw away from the frame and be wholly free as indicated by 70 its position in dotted lines, Fig. 3.

As in the pending application Serial Number 412,449, before referred to, a drain board 30, also of metal may be arranged to lie below housings 31, formed on the inside 75 of the upright end portions of the frame for the outer ends of the squeeze rolls, and this drain board may be adjustably held in place in the same manner as illustrated in said application. The usual guide plates 32 to 80 direct the garments to the bite of the squeeze rolls may be employed, as in all similar structures; said guide plates having projections 85 33 which engage the edges of the housings 31.

Power to drive the squeeze rolls may be applied to either spindle but in the present case we have shown the lower spindle as 90 projecting beyond the end of the frame, as indicated at 6^a, for operative engagement with a driving element; the shaft of a suitably actuated motor for instance. In lieu of this, the projecting spindle may be engaged by a suitable crank-handle, or other 95 form of power-applying member.

As in the structure of the pending application Serial Number 446,226 before referred to, it will be readily understood that if both cap members 13 and 14 are released 100 from their spring engagement with the frame and swung back on their hinged connection with the upright end portions thereof, the squeeze-rolls 7, with the bearing blocks 5, may be removed. This permits ready assembly and removal of the various 105 parts of the structure, for renewing the bearings or squeeze-rolls or other repairs, as occasion may require. There are no parts to get out of order or readily break, and any 110 suitable form of clamping device may be employed to attach our improved wringer to a washing machine or tub, or at any other desired point.

It will be understood that we do not wish 115 to be limited to the exact construction disclosed in the drawings and described herein, and our claims are designed to cover any equivalent construction having the same or a similar object in view. It will also be understood that our improvements may be applied to wooden or metal frames, and that the latter may be made of cast or pressed metal, without departing from our invention.

We claim:

1. In a clothes wringer, the combination with a frame having upright end portions, squeeze rolls operatively mounted in said frame, cap members hinged to said end portions, spring bolts pivotally mounted in 120

said cap members and engageable with the frame for holding said cap members in place and applying tension to said squeeze rolls and means carried by said cap members for transmitting pressure to the squeeze rolls, of means disposed at one end of the frame for releasing one of said spring bolts and a cap member connected thereto whereby the pressure exerted to keep the squeeze rolls in operative engagement may be instantly relieved.

2. In a clothes-wringer, the combination with a frame having hollow upright end portions, removable bearing blocks fitting within said hollow end portions, squeeze-rolls having spindles in operative engagement with said blocks, cap members hinged to said end portions, spring bolts pivotally mounted in said cap members and engageable with the frame for holding said cap members in place, and lugs carried by said cap members for engaging the upper bearing blocks of the squeeze-rolls, of means disposed at one end of the frame for releasing one of said spring bolts and the cap member connected thereto, whereby the pressure exerted to keep the squeeze-rolls in operative engagement may be instantly relieved.

3. In a clothes-wringer, the combination with a metal frame having upright end portions, squeeze-rolls mounted in said frame; cap members hinged to said upright end portions, and means including spring bolts pivotally mounted in said cap members and engageable with the frame for holding said cap members in operative engagement with the upper squeeze-roll whereby the necessary pressure may be applied to the rolls, of a knock-off handle connected to one of the cap members whereby said cap member may be quickly released to relieve the pressure exerted to keep the squeeze-rolls in operative engagement with each other.

4. In a clothes-wringer, the combination with a frame having upright end portions; squeeze-rolls mounted in said frame, cap members hinged to the upright end portions and in operative engagement with the squeeze-rolls and spring bolts pivotally mounted in said cap members and engageable with the frame for holding said cap members in place and applying tension to said squeeze-rolls, of an extension connected to one of said spring bolts and constituting means whereby the latter can be swung on its pivot and instantly released from its operative engagement with the wringer frame and simultaneously relieve the pressure exerted to keep the squeeze rolls in operative engagement with each other.

5. In a clothes-wringer, the combination

with a frame having hollow upright end portions; bearing blocks adapted to said end portions, squeeze-rolls having spindles in engagement with said bearing blocks, cap members hinged to the upright end portions, said cap members having lugs in engagement with the upper bearing blocks, and pivotally mounted spring bolts engageable with the frame for holding said cap members in place and applying tension to said squeeze-rolls, of an extension connected to one of said spring bolts and constituting means whereby the latter can be swung on its pivot and instantly released from its operative engagement with the wringer frame and simultaneously relieve the pressure applied to the squeeze rolls.

6. In a clothes-wringer, the combination with a frame having upright end portions, squeeze-rolls mounted in said frame, cap members hinged to said upright end portions and in operative engagement with the squeeze-rolls and spring bolts pivotally connected to said cap members and engageable with the frame for holding said cap members in place and applying tension to said squeeze-rolls, of an upright extension carried by one of said spring bolts, and a hand plate carried by said extension and overlying the squeeze-rolls and constituting means whereby the spring bolt can be swung on its pivot and instantly released from its operative engagement with the wringer frame and simultaneously relieve the pressure applied to the squeeze-rolls.

7. In a clothes-wringer, the combination with a frame having upright end portions, bearing blocks fitting within said end portions, squeeze rolls mounted in said frame and having spindles in engagement with said bearing blocks, cap members hinged to said upright end portions, said cap members having lugs in engagement with the upper bearing blocks, and spring bolts pivotally connected to said cap members and engageable with the frame for holding said cap members in place and applying tension to said squeeze-rolls, of an upright extension carried by one of said spring bolts, and a hand plate carried by said extension and overlying the squeeze rolls and constituting means whereby the spring bolt can be swung on its pivot and instantly released from its operative engagement with the wringer frame and simultaneously relieve the pressure applied to the squeeze-rolls.

In witness whereof we have signed this specification.

FREDERICK GEORGE SCHRANZ.
WILLIAM H. HARMAN.
